(57) **CLAIM**

The ornamental design for a cylindrical soap pump dispenser, as shown and described.

DESCRIPTION

FIG. 1 is a top front and left perspective view of my new design;

FIG. 2 is a top plan view thereof;

FIG. 3 is a front view thereof;

FIG. 4 is a right side view thereof, the left side view being a mirror image thereof; and,

FIG. 5 is a rear view thereof.

The bottom plan view is plain and unadorned, and forms no part of the claimed design.
